UNITED STATES PATENT OFFICE.

JENS P. ANDERSEN, OF BROOKLYN, WISCONSIN.

BOB-SLED.

1,182,128.

Specification of Letters Patent.

Patented May 9, 1916.

Application filed May 22, 1915. Serial No. 29,808.

To all whom it may concern:

Be it known that I, JENS P. ANDERSEN, citizen of the United States, residing at Brooklyn, in the county of Green and State of Wisconsin, have invented a new and useful Bob-Sled, of which the following is a specification.

The invention relates to improvements in bob sleds.

10 The object of the present invention is to improve the construction of bob sleds, more especially that shown and described in an application filed by me on the 8th day of April, 1914, Serial No. 830,557, and to provide a simple, practical, and efficient bob sled of strong and durable construction, adapted to permit a free rocking movement of the runners in passing over uneven ground.

20 A further object of the invention is to improve the construction of the means for operating the front runners, which have independent horizontal pivotal movement, and enable the sled to be easily turned without liability of tipping over.

25 With these and other objects in view the invention consists in the construction and novel combination of parts hereinafter fully described, illustrated in the accompanying drawings, and pointed out in the claims appended hereto, it being understood that various changes in the form, proportion, size and minor details of construction, within the scope of the claims, may be resorted 30 to without departing from the spirit or sacrificing any of the advantages of the invention.

35 In the drawings:—Figure 1 is a perspective view of a bob sled constructed in accordance with this invention. Fig. 2 is a 40 longitudinal sectional view of the bob sled, parts being in elevation. Fig. 3 is a bottom plan view of the front portion of the bob sled. Fig. 4 is a vertical longitudinal detail sectional view through the front bolster, knee and runner. Fig. 5 is a transverse sectional detail view of the bolster, knee and runner. Fig. 6 is a vertical longitudinal sectional view through the rear portion of the 45 bob sled, illustrating the construction for securing the rear runners to the rear bolster. Fig. 7 is a transverse sectional detail view through the bolster, knee and runner. Fig. 8 is a detail sectional view on the line 8—8 50 of Fig. 2. Fig. 9 is a detail sectional view on the line 9—9 of Fig. 1. Fig. 10 is a

detail sectional view on the line 10—10 of Fig. 2. Fig. 11 is a perspective view of the pivoted bearing block, and Fig. 12 is a perspective view of the stationary bearing 60 block.

Like numerals of reference designate corresponding parts in all the figures of the drawings.

65 In the accompanying drawings, in which is illustrated the preferred embodiment of the invention, 1 and 2 designate front and rear bolsters connected by a reach 3 composed of adjustable front and rear sections 4 and 5 slidably connected with each other by front and rear cuffs, 6 and 7. The front reach section 4 is superimposed upon the rear reach section 5, and the front cuff 6, which is secured to the front end of the rear reach section 5 by a bolt or other suitable 70 means, loosely embraces the front reach section 4 and is provided at the top with a perforation 8 adapted to register with perforations 9 of the front reach section 4 in which a pin 10 is received to secure the reach sections 4 and 5 in their adjustment. The pin 10 is secured to a chain or other flexible connection 11, which has its other end attached to the bob sled. The rear cuff 7, which is bolted or otherwise secured to the rear end of the front reach section, slidably embraces the rear portion of the rear reach section. 75

80 The front reach section 4 is rigidly connected with the front bolster 1 by upper and lower plates 12 and 13. A flange 14 of the upper plate 12 is connected to the rear face of the front bolster, and the lower plate 13 is provided at its front end with a pair of 85 forwardly diverging terminals 15 which are secured to the lower face of the front bolster. 90

95 The rear portion of the reach section 5 extends beneath the bolster 2 and is loosely connected and suspended therefrom by a hanger 16, consisting of a body portion 17 bolted or secured to the upper face of the rear section 5 and provided at opposite sides 100 with depending flanges 18 which embrace the side edges of the rear reach section. The hanger 16 is provided at the front and back of body portion 17 with upwardly extending ears or flanges 19, arranged on opposite sides of the bolsters and loosely connected with the same by a bolt 20 or other suitable fastening device, the bolt 20 fitting loosely 105 in the ears 19 and the bolster to allow the reach to receive a rotary movement. 110

The rear bolster is supported at its ends

by knees 22, constructed of suitable metal and consisting of oppositely inclined front and rear sides 23 connected at the top by an arched or curved portion 24. Stationary bearing blocks 25, preferably of malleable castings, are connected to the lower sides of the bolster 2 and are provided with recesses 25^a in which the arched or curved portions 24 are received. Pins 26 pass through the ends of the blocks 25 and beneath the knees 22 for fastening the knees to the bolster. Cotter pins 26' pass through the pins 26 to hold them in place. The lower ends of the inclined sides 23 have terminal attaching portions 27 which engage the top and a side of the runners 21 and are bolted or otherwise secured to the runners.

The front bolster 1 is supported by knees 28 mounted upon runners 29 and composed of oppositely inclined sides 30 and curved or arched top portions 31 connecting the sides. Connected to the underside of the bolster 1, and at the opposite ends thereof, are plates 32. A bearing block 33 is connected to each plate 32 by a stud or rivet 34 which permits the bearing block 33 to rotate upon the plate 32. The bearing blocks 33 are recessed, as at 35 for the reception of the arched portions 31 of the knees 28. Pins 36 pass through the ends of the bearing blocks and beneath the knees 28 for fastening the knees to the bearing blocks. Cotter pins 37 pass through the pins 36 for holding the pins in position.

Bearing blocks 33 permit the runners 29 to have an oscillatory movement in a vertical or horizontal plane, while the bearing blocks 25 of the rear bolster 2 allow the runners 21 to have an oscillatory movement in a vertical plane. This rocking or oscillating movement in a vertical plane permits the runners to pass over obstructions or uneven surfaces, and the rear bolster 2 can rock or oscillate transversely of the reach when the runner passes over an obstruction as it has a pivotal connection with the reach through the hanger 16. The side walls of the bearing blocks are adapted to engage the sides of the knees for limiting the oscillatory movement of the knees in a vertical plane.

The inclined sides 30 are provided at their lower ends with attaching portions 38, the attaching portions being secured to the upper faces and sides of the runners.

The front runners 29 are equipped at their front ends with vertical pivots 39, preferably consisting of bolts passing through metallic straps 40 and 41. The metallic strap 40 is bent approximately U-shape, and extends around the front end of each front runner, is disposed longitudinally of the same and is secured at its terminals to the upper and lower faces of the runner. The other metallic strip 41, which is also bent into approximately U-shape, is

disposed transversely of the front end of the front runner and extends across the same and is secured to the side faces thereof, as clearly illustrated in Fig. 9 of the drawings. Each pivot bolt 39 is provided at its lower end with a head 42, which is arranged in a recess 43 in the front end of the front runner, and a nut 44 engages the upper face of the transversely disposed metallic strap and firmly clamps the straps between it and the head on the bolt. The said metallic straps 40 and 41 form caps which reinforce the front portion of the front runners and firmly support the pivots 39 in a vertical position.

The vertical pivots 39 pass through openings 45 in the terminal portions of a transverse connecting bar or member 46 which connects the forward ends of the runners together, and connected to the bar 46 is a draft bar or member 47. The transverse connecting bar 46 which is preferably constructed of flanged metal, has the terminal portions 48 of one of the wings or flanges thereof flattened, and the flattened portions of the connecting bar are retained on the vertical pivots 43 by nuts 49 or other suitable fastening means. The transverse connecting bar 46 causes the runners to turn in unison on the vertical stems or pivots 34, which connect the knees 28 with the bolster 1. The draft bar or member 47 consists of an approximately straight bar 50 and an approximately U-shaped yoke 51, composed of spaced sides and a connecting rear portion, the forward end 52 of the bar 50 being bent upwardly within the yoke 51 and secured thereto. The sides of the yoke are connected at their forward ends by a transverse bottom plate 53 having upwardly extending side portions 54 which are secured to the outer faces of the sides of the yoke 51. The yoke is also connected to the transverse bar or member 46 by a vertical pivot bolt 55 passing through the transverse plate 53 and the connecting bar or member 46, and also piercing bearing disks or plates 56-57 constituting a fifth wheel and secured respectively to the bottom plate 53 of the yoke and to the transverse bar or member 46. The rear end 58 of the bar 50 is bent downwardly and extended through an opening 59 of a link 60, which is adjustably secured to the front reach section at the lower face thereof by a vertical pivot bolt 61. The link 60 is provided with a plurality of openings 62, adapted to receive the pivot bolt 61 to permit a downward or forward adjustment of the link which connects the rear end of the draft bar or member 47 to the frame of the bob sled. The front portion of the link 60 is bent downwardly and offset from the lower face of the bottom plate 13 of the front reach section and the rear end 58 of the said bar 50 is secured in the open-

ing on the link by a key 63 or other suitable fastening device, a washer 64 being preferably interposed between the key and the front portion of the link.

5 A tongue or pole 65 is pivoted at its rear end within the yoke 51 by a bolt 66 located in rear of the bottom plate 53 which receives and supports the said tongue or pole 65. The tongue or pole is adapted to swing 10 upwardly from the supporting plate 53 and when it is swung laterally to turn the bobsled, it carries with it the transverse connecting bar 46 which causes the front runners to turn simultaneously on the vertical 15 stems or pivots of the front knees.

The front ends of the rear runners are connected with each other by a substantially V-shaped connecting rod 67, composed of forwardly converging sides connected at 20 their front ends by an eye 68 which is linked into a loop 69 depending from and carried by the front portion of the rear section 5 of the reach. The rear ends of the sides of the V-shaped connecting rod 67 are provided 25 with eyes 70 which are linked into eyes 71 projecting from the inner faces of the rear runners 21 at the front portions thereof. The eyes and the said loop constitute pivotal connections so as not to interfere with the 30 rocking movement of the rear runners.

What is claimed is—

1. A bob sled including a front bolster, front runners pivotally connected to the front bolster and having a horizontal oscillatory movement, a transverse bar connecting the front portions of the front runners and located in advance of the bolster, a central longitudinal draft bar pivotally connected at its rear end to the sled, a U-shaped 35 yoke connected to the outer end of the draft bar, a plate pivotally connected to the transverse bar having side portions connected to the yoke for connecting the yoke to the transverse bar, and a tongue connected to 40 said yoke.

2. A bob sled including a front bolster and a reach, front runners pivotally connected with the front bolster and having a horizontal oscillatory movement independently of the bolster for changing the direction of the sled, a transverse bar connecting the front portions of the front runners and located in advance of the front bolster, a central longitudinal draft bar or member 45 pivotally connected at its rear portion with the reach and provided at its front portion with a tongue receiving yoke composed of spaced sides and a connecting rear portion, and a transverse bottom plate connecting the 50 front portions of the sides of the yoke, bear-

ing plates secured to the bottom plate and to the transverse bar, and a pivot connecting the bearing plates.

3. A bob sled including a rear bolster, rear runners supporting the rear bolster, a reach, 65 and a hanger rigidly secured to the reach and provided with upwardly extending front and rear portions embracing the rear bolster and pivoted to the same.

4. A bob sled including a rear bolster, rear 70 runners supporting the rear bolster, a reach, a hanger consisting of a plate or body rigidly secured to the reach and provided with depending side flanges embracing the said reach, said plate or body being also provided with upwardly extending front and rear flanges arranged at the front and rear faces of the rear bolster, and a horizontal pivot piercing the front and rear flanges 75 and the bolster. 80

5. A bob sled comprising a bolster and a runner, a longitudinally recessed bearing block pivotally mounted upon the bolster, a knee connected to the runner having the upper end thereof received in the recess of 85 the bearing block, and means passing through the bearing block and beneath the knee for fastening the knee to the bearing block whereby the knee may oscillate with respect to the bearing block. 90

6. A sled comprising a bolster and runner, a plate connected to the bolster, a bearing block, a stud connecting the plate and bearing block together so that the bearing block is capable of horizontal movement, a knee 95 connected to the runner and a transverse pin passing through the bearing block and beneath the knee for pivotally connecting the knee to the bearing block.

7. A bob sled comprising a bolster and a 100 runner, a recessed bearing block pivotally mounted on the bolster, a knee connected to the runner composed of front and rear inclined sides, said sides being connected together at their upper ends and diverging 105 therefrom forming a curved connecting top portion, said curved connecting top portion being received in the recess of the bearing block, and a pin passing through the bearing block lengthwise of the recess and beneath the knee for fastening the knee to the bearing block, whereby the knee may operate independently of the bearing block. 110

In testimony, that I claim the foregoing as my own, I have hereto affixed my signature in the presence of two witnesses.

JENS P. ANDERSEN.
